INVENTOR

Ferdinand E. Kauffmann,
BY
Mrs. H. Kauffmann
ATTORNEY.

UNITED STATES PATENT OFFICE.

FERDINAND E. KAUFFMANN, OF RAHWAY, NEW JERSEY.

MACHINE FOR FINISHING THE EDGES OF HAT BRIMS.

Application filed December 31, 1920. Serial No. 434,234.

To all whom it may concern:

Be it known that I, FERDINAND E. KAUFFMANN, a citizen of the United States, and a resident of Rahway, county of Union, and 5 State of New Jersey, have invented certain new and useful Improvements in Machines for Finishing the Edges of Hat Brims, of which the following is a specification.

This invention relates to an improved machine for treating the edges of hat brims, and is particularly adapted for treating the edges of the brims of velour hats.

At present, when the hat brim is cut along its edges by the usual device, which consists 10 of a knife on a gage, by means of which the distance from the crown of the hat is regulated, the very edge of the brim shows the body of the hat and the soft furry appearance of the rest of the hat is missing from 15 the edge of the brim. A number of ways have been devised to overcome this, one being to make the brim half the thickness of the hat body, but twice its normal width, and provided with a furry face on only one side, 20 and then folding this over with the furry side out to form the hat brim, but this method is unsatisfactory and expensive.

I have devised a machine which treats the edge of the brim so that the step of cutting 25 is eliminated and the hat brim is given the proper width and also the proper edge at practically the same time, and it requires but one action by the machine, and when the hat is removed from the machine the 30 edge of the brim is at the required distance from the crown and has the same appearance as the rest of the hat.

The invention is illustrated in the accompanying drawings, in which Figure 1 is a 35 front view, several parts being broken away, this view showing one form of my improved machine. Figure 2 is a top view of the machine shown in Figure 1. Figure 3 is a vertical section of the trimming mechanism 40 shown in Figures 1 and 2. Figures 4 and 5 are detail views of the carding and brushing means shown in Figure 3. Figure 6 is a detail view showing the appearance of the finished edge of the hat brim. Figure 7 is 45 a section of a modified form of means for holding the hat in position, and Figures 8 and 9 are detail views showing modified forms of brushing mechanism for the edge of the hat.

In the form of machine illustrated as one embodiment of my invention 50 is a standard

which supports, at the top, a suitable hat support. The hat support 11 is rotatable and includes a brim supporting flange 12 which is secured on a shaft 13 which extends 55 down into the standard 10 and is rotated by suitable means. It is desirable to have the hat rotate comparatively slow, and to accomplish this I show a worm gear 14 driven by a worm 15 on the main shaft 16, which in 60 turn is driven by the pulley 17 and the belt 18.

To hold the brim 19 of the hat 20 down, I place a flange 21 which forms a clamp, being 65 of considerable weight and having a handle 22 for its manipulation. The brim holding flanges cover the major portion of the brim and present, therefore, a comparatively small edge to be treated, and this is held 70 comparatively stiff.

The mechanism for treating the edge of the brim is one that brushes the edge usually 75 straight across and in opposite directions. In the drawings I show a brush 23 on the shaft 24 which is driven by the belt 25 and pulleys 26 and 27 from the main shaft 16. A brush 28 is rotated by the shaft 29 which is driven by the belt 30 and pulleys 31 and 32 from the main shaft 16. The belt 30 is 80 crossed and the belt 25 is not, so that the brushes 23 and 28 are rotated in opposite 85 directions.

The gearing of the brushes is such that 90 they rotate at a high rate of speed compared with the speed of the rotation of the hat. The shafts 24 and 29 are mounted in standards 33 which are connected, as at 34, so that 95 they move together and are mounted in a suitable support 35, these standards, which I will call the support, being slidable in the base 35, which base is fastened, as at 36, to the standard 10 and is held thereon against rotation.

A yielding means, such as the weight 37, tends, through the cable 38, to pull the support, and consequently the brushes, toward 100 the hat brim until the support 33, by means of its arm 39, engages, through the roller 40, the cam 41 on the hat support. This cam 41, as will be seen from Figure 2, is somewhat 105 elliptical to conform to the shape of the hat crown, so that as the hat rotates, the brushes are retreated or are advanced, according to whether the broader or the narrower part of the hat is presented to the brushes. A handle 42 is provided whereby the brushes can be 110 retreated away from the hat brim, which is

desirable, for instance, when the hat is to be removed and a new hat put in position. Belt tighteners 43 insure the belts 25 and 30 remaining tight while the brush support is at its various positions.

In order to shorten the time necessary to reduce the hat brim to the required size, I provide, in addition to the brushes 23 and 28, slightly more rigid elements to act on the hat first. The brushes 23 and 28 are made of very fine wire, and in advance of the brush 23 I prefer to arrange heavier wires 44, and in advance of these a shredder 45. It will be seen from Figure 2 that the hat is first engaged by the shredder 45 which has teeth 46 thereon and which is made usually from a thin disk of metal, and the teeth, rotating at a high rate of speed while the hat rotates slowly, successively pull from the hat small particles, then the carding wires 44 will further cut down the amount of material and then the fine brushes 23 and 28, one rotating in one direction and one in the other, fluff the material, so that when completed, the edge of the hat brim, shown at 47 in Figure 6, has the same appearance as the rest of the hat and none of the body of the hat is presented to view.

In order to carry off the fur that is taken from the edge of the brim I provide a cap 48 which is connected, through the casing 49, with the tube 50 which is connected to a suitable source of suction, so that the hair and fur is withdrawn from the machine and can thus be conserved. Furthermore, the health of the operator is not impaired by reason of this hair and these fur particles floating in the air.

The method of operation is to place a hat on the hat support and then deposit the flange 21 on it. The machine is put in operation by a suitable clutch, which is not shown and which can be of the ordinary stop type which will operate the machine for, say, two revolutions of the hat and then automatically stop. This device is not shown as it forms no part of this invention and is an ordinary article of commerce. As the hat rotates, the rapidly revolving shredder and the brushes cut down the diameter of the brim slightly, as will be seen from Figure 2, and after the hat has made two full revolutions the edge of the hat brim is finished. I prefer to normally have the brushes 23 and 28 of slightly larger diameter than the carding wires 44 and the shredder 45.

In Figure 7 I show a modified form of hat support in which the weighted part 21 can be eliminated, in this construction the flange 60 12 having a metal strip 51 which is connected by wires 52 with a source of electrical energy, and a light metal hat clamp 53 is put in place and it holds the hat brim down by reason of its attraction to the magnetic 65 ring 51.

In Figure 8 I show a modified form of brush, this brush 54 being arc-shaped and being pivoted, as at 55, and reciprocated by a suitable mechanism, such as the arm 56, so that the single brush will operate to fluff or brush the fibre of the hat in both directions. This reversal of direction is preferred, because if the fibre is brushed all in one direction it causes a semi-permanent "lay" of the fur in one direction. 75

A still further modified form of brush is shown in Figure 9, the brush 57 being of a continuous or belt type rotating on the pulleys 58, and it will be evident that when two of these brushes are employed, one operating in one direction and one operating in the opposite direction, the same result is secured as that when the brushes 23 and 28 are used or when the brush 54 is used. 80

It will be evident that minor changes 85 may be made in the form of the machine and in the assembling of the parts without departing from the scope of the invention.

I claim:

1. A machine for finishing the edges of 90 the brims of velour hats comprising a hat holding means including a support for the hat brim, a brushing mechanism to brush across the edge of the brim, and means for causing the brushing mechanism to successively engage adjacent portions of the hat brim. 95

2. A machine of the kind described comprising a hat holding means including a support for the hat brim, and means for 100 brushing across the edge of the hat brim in two directions.

3. A machine of the kind described comprising a hat holding means including a support for the hat brim, a brushing means, 105 and means for holding the brushing means so as to brush across the edge of the hat brim to form a predetermined width of hat brim.

4. A machine of the kind described comprising a hat holding means constructed so as to hold the brim of a hat in flat form, a carding device to operate across the edge of the hat brim to reduce its diameter, and brushing means for brushing the carded 115 edge in opposite directions.

5. A machine of the kind described comprising a hat holding means, means for rotating the hat holding means, a brushing means, means for supporting the brushing means so that the brushing means operates across the edge of the brim, and a cam on the hat support and engaging the means for supporting the brushing means. 120

6. A machine of the kind described comprising a hat support constructed so as to present the edge of the brim, means for rotating the hat support, said hat support including a cam, a brushing means, means for supporting the brushing means so that the 125 130

brushing means operates across the edge of the brim, said supporting means being in engagement with the cam, and a yielding means for holding said brushing means in engagement with the cam.

7. A machine of the kind described comprising a hat support, means for clamping the brim in said hat support so as to present the edge of the brim for treatment, means 10 for rotating the hat support, brushing means including a shredding mechanism, carding wires and a brush arranged closely adjacent

to each other and rotatable in one direction, a second brush arranged to rotate in the opposite direction, means for rotating these 15 elements in their respective directions, and yielding means for holding the said elements so that they operate across the edge of the hat brim at predetermined distances from the body of the hat.

In testimony that I claim the foregoing, I have hereto set my hand, this 29th day of December, 1920.

FERDINAND E. KAUFFMANN.
